CLAIM

We claim the ornamental design for a satellite speaker, as shown and described.

DESCRIPTION

FIG. 1 is a perspective view of a satellite speaker, showing our new design;

FIG. 2 is a front view of the satellite speaker;

FIG. 3 is a rear view of the satellite speaker;

FIG. 4 is a first side view of the satellite speaker;

FIG. 5 is a second side view of the satellite speaker;

FIG. 6 is a top view of the satellite speaker; and,

FIG. 7 is a bottom view of the satellite speaker.

The portions shown in broken lines form no part of the claimed design.
